UNITED STATES PATENT OFFICE.

KENNETH RUSHTON, OF PHILADELPHIA, PENNSYLVANIA, ASSIGNOR TO BURNHAM, WILLIAMS & COMPANY, OF PHILADELPHIA, PENNSYLVANIA, A FIRM.

RELIEF-VALVE FOR LOCOMOTIVES.

SPECIFICATION forming part of Letters Patent No. 749,101, dated January 5, 1904.

Application filed November 23, 1903. Serial No. 182,294. (No model.)

To all whom it may concern:

Be it known that I, KENNETH RUSHTON, a citizen of the United States, residing in Philadelphia, Pennsylvania, have invented certain 5 Improvements in Relief-Valves for Locomotives, of which the following is a specification.

My invention relates to certain improvements in relief-valves for locomotives which prevent the formation of a partial vacuum in 10 the low-pressure cylinder of a compound engine and the passages leading thereto and which also prevent the accumulation of steam in the low-pressure cylinder due to a leaky throttle.

15 Heretofore the relief-valve was carried by the valve controlling the flow of steam to and from the cylinders.

The object of my present invention is to so construct the device that the relief-valve will 20 be stationary. This object I attain in the following manner, reference being had to the accompanying drawings, in which—

Figure 1 is a sectional view of sufficient of 25 the saddle of a locomotive to illustrate my invention, and Fig. 2 is a sectional view illustrating a modification.

A is a portion of the saddle of a locomotive having the valve-chest B, in which reciprocates the piston-valve D, which I will term 30 the "cylinder-valve." This valve is connected to the valve-rod D', which extends through a stuffing-box b' in the forward cap B' and controls the flow of steam to and from the cylinders.

35 S S are the steam-ports leading from the boiler.

H H are the ports leading from the high-pressure cylinder.

40 L L are the ports leading from the low-pressure cylinder, and E is the exhaust-port.

The arrangement of the ports may differ, according to the type of engine to which my invention is applied.

The cylinder-valve D has a head d at the 45 forward end and a head d' at the rear end. d² d² are ports connecting with the interior of the valve, and d³ is an annular channel connecting with the exhaust-port. It will be seen that the interior of the valve forms a passage to allow the steam to flow from the high-

pressure port on one side to the low-pressure port on the opposite side.

In the rear cap or cover-plate B² is formed a chamber b², which connects with the relief-valve chest F and with the interior of the 55 valve D through a tube b, which is screwed into the cap B² and extends through the stuffing-box d⁴ in the head d' of the valve D. Any suitable packing d⁵ can be used in the box.

The relief-valve chest F has a stem f, which is screwed into the projection on the cap B² and forms a communication with the chamber b², and screwed into the valve-casing F is a cage f', which carries the valve-seat f² for the valve G. Surrounding the cage is a 60 cover F', secured to the cage by means of a nut f³ on the stem f⁴. When the valve is open, it rests upon the shoulder f⁵ on the valve-casing. 65

In Fig. 2 I have shown a different form of 70 relief-valve casing. The chamber in this instance is reduced, and the valve-inlet is on a line with the tube b. The valve-casing F² has a seat i, against which the valve G' closes, and this valve is supported when open on a projection of the cap F³. Openings i' in the valve-casing allow for the ready inlet of air. 75

It will be seen by my improvement that the relief-valve is fixed in respect to the cylinder-valve, and the projecting tube b extends from 80 the rear cap through a stuffing-box in the end of the cylinder-valve and communicates at all times with its interior, and consequently through the ports to the cylinders, and the locomotive can drift without creating a vacuum in the low-pressure cylinder or the passages leading thereto, as when steam is cut off the relief-valve will open and air will be drawn through the tube into the central portion of the cylinder-valve. This construction will prevent locomotives starting owing to leaky throttles, as the steam when it escapes will pass through the tube b and around the valve. It will be understood that the relief-valve in its normal position is open; but 85 as soon as a quantity of steam is admitted to the valve-chest by opening the throttle the pressure will immediately close the relief-valve G against its seat and hold it there during the normal working of the locomotive. 90

I claim as my invention—

1. The combination in a compound locomotive, of a valve-chest, a hollow cylinder-valve therein controlling the flow of steam to 5 and from the cylinders, a relief-valve fixed to the chest and communicating with the interior of the said cylinder-valve, substantially as described.
2. The combination in a valve-chest having 10 ports leading to the high and low pressure cylinders, a valve in said chest having a hollow center, a relief-valve carried by one of the caps closing the valve-chest, a tube extending from the cap and through one end of 15 the cylinder-valve, and communicating with the relief-valve, substantially as described.
3. The combination in a valve-chest having 20 ports communicating with the high and low pressure cylinders, a valve in said chest, said valve closed at each end forming a chamber, a cap closing the end of the valve-chest, a relief-valve carried by the said cap, a tube extending inwardly from the cap and through
- one end of the hollow valve so as to form a communication between the interior of the 25 said valve and the relief-valve, one end of the hollow valve having a stuffing-box through which the tube extends, substantially as described.
4. The combination in a valve-chest having 30 ports leading to the high and low pressure cylinders, a hollow cylinder-valve having heads at each end, a cap closing the end of the valve-chest, a tube secured to said cap and extending through one end of the cylinder-valve, said cap having a chamber, a relief-valve casing communicating with said chamber, and a relief-valve in said casing, substantially as described.

In testimony whereof I have signed my 40 name to this specification in the presence of two subscribing witnesses.

KENNETH RUSHTON.
